HEATING ELEMENT FOR DRYING APPARATUS

Auguste Bergmann, Reims, France

Application December 13, 1934, Serial No. 757,258
In France December 14, 1933

4 Claims. (Cl. 257—248)

The invention herein described relates to drying chambers in which textile fibres, threads in layers or in hanks, fabrics, paper and like material are dried by means of the circulation of hot air.

5 In particular, it relates to drying chambers in which the materials to be dried travel over a continuous zig-zag path, between partitions, or plates arranged as baffle-plates, each such baffle-plate occupying almost the whole length of the chambers and extending in a transverse direction over 10 the entire width of the said chambers, from one lateral wall to the other, the heating elements, such as in general tubes heated by the circulation of steam, being arranged above and below 15 the said baffle-plates, and the air thus heated circulating between the baffle-plates, its direction of flow being either the same as that of the materials to be dried or opposite to this.

The object of the invention is to improve the 20 efficiency of the above-mentioned system of heating by means of heating baffle-plates, with a view to supplying the necessary heat at each point of the path of the material to be dried which will compensate for the heat absorbed by the evaporation, 25 the amount of heat depending on the degree of humidity of the material and the degree of saturation of the surrounding air at each point in question, and the improvement being effected owing to the fact that the heating surfaces are 30 in direct contact with the air circulating between the baffle-plates. The invention also has as another object an improved construction, making it more practical and easier to install, more economical to construct and adaptable to the above- 35 mentioned classes of drying chambers.

With these objects in view, the invention consists of the provision of heating units or elements that may be arranged to provide a drying chamber having a zig-zag course for the material to 40 be dried.

Heating elements or units embodying the invention are disclosed in the accompanying drawing in which:

45 Fig. 1 is a longitudinal, sectional elevation illustrating the type of drying chamber to which the heating units of this invention are especially applicable;

Fig. 2 is a longitudinal, sectional elevation of 50 three of the units embodying the invention, the two end units being broken away and a section being taken along the line II—II of Fig. 3;

Fig. 3 is a transverse, sectional elevation of the 55 heating unit illustrated in Fig. 2, the section being taken along the line III—III of Fig. 2; and

Fig. 4 is a transverse, sectional elevation of a modified form of heating unit, the transverse, sectional elevation being the same as that of Fig. 2.

The drying chamber illustrated in Fig. 1 consists of a metal cabinet having side walls 1. Within the cabinet, adjacent one end, there is a guide roller 2 and at the front of the cabinet there are guide rollers 3 and 4. The material 5 to be dried passes over the guide roller 3 and enters an opening through the front wall of the chamber, passes through the chamber to the guide roller 2 and back to the front of the chamber and over the guide roller 4. Two passages at different elevations through which the material 5 passes are formed by a series of heating units.

Heating units which when arranged in several series form a drying chamber similar to that disclosed in Fig. 1, are illustrated in Figs. 2 and 3. The units illustrated in Figs. 2 and 3 include a group of metal tubes 9, the length of which is greater than the width of the drying chamber in which the heating elements are mounted. The diameters of these tubes may be equal or the several tubes may vary in diameter. A series of rectangular plates 10 and two end plates 10', preferably made of aluminum, are mounted on these tubes. The plates 10, 10' and the walls 1 have cut therethrough holes to receive the tubes 9. The holes in the plates and the tubes may be arranged in undulating lines such as indicated in Fig. 2 or otherwise as desired. The plates are spaced apart and the edges thereof may be stamped so as to follow the undulating lines of the rows of tubes on which they are mounted. Metal strips 11 maintain the plates in spaced relation. These metal strips 11 are mounted between successive plates and rest upon the tubes 9. The strips 11 follow the undulating lines of the rows of tubes.

40 The strips 11 are secured to the plates 10 by solder 12. In addition to this soldering, each element can be, if required, dipped into a soldering bath after it has been constructed, so as to fill up and seal all the interstices which may exist between the tubes and the plates 10. Any mechanical means may also be utilized for the same purpose during the construction of each element, in order to fasten the plates of metal 10 on the pipes 9: for example, expanding mandrels may be passed into the interior of the pipes, in order to expand the pipes in the plates 10.

45 In order to facilitate and at the same time to reinforce the assembly of the elements to form 50

a heating baffle-plate, the lateral edges of the plates 10 may be provided with steps 13 or recesses or projections so as to permit the fitting edge to edge of the said plates.

5 Moreover, the central part of the plates 10 may be provided, between the rows of tubes 9, with one or several apertures 14, in order to permit communication between the spaces separated by the plates, and at the same time to 10 lighten the weight. The two end plates 10', however, are not provided with such apertures, in order that the element may form hollow airtight baffle plates constituting a heating chest, having surfaces with circumvolutions to improve 15 the mixing of the air.

For the construction and the assembly of the heating baffle-plates in a drying chamber, the elements formed as above described are arranged for each baffle-plate one after the other, and 20 these are assembled in the same plane, between the lateral walls 1 of the chamber, the ends of the tubes 9 passing beyond the end plates 10' of an element and being supported on the lateral walls of the chamber, through which they pass by 25 means of holes provided there and arranged in the same way as in the plates 10, all the ends of the tubes 9 being connected on an outer wall of the chamber by collecting pipes (not shown) which feed the steam to the chamber, whilst all 30 the opposite ends of these tubes are connected by outlet collector pipes, the heating elements thus assembled form baffle-plates extending alternately from the front wall 1 of the chamber to a certain distance from the rear wall 1, and vice-versa. These units are so arranged that a series 35 of units form one longitudinal baffle in the drying chamber and another series of units mounted above form with the lower series of units a transverse passage through which the material to be dried passes.

In a variation of the invention shown in Figure 4, the construction of an element remains approximately similar, with the difference that the group of tubes 9 is eliminated and the chest 45 formed by the assembly of the plates 10 and the intervening strips 11 receives the steam direct, which thus fills all the hollow partition or plate forming a baffle, the admission and discharge of the steam being ensured by external lateral pipes 50 in a suitable number, which pass through the walls of the chamber and end in the elements

forming each heating baffle-plate, which elements may also be made by drawing or casting.

It is well understood that, without departing from the spirit of the invention, modifications, improvements and additions may be made, and also the employment of equivalent means adopted.

I claim:

1. A heating unit for drying chambers of the type described comprising a plurality of metal plates spaced apart and arranged in parallel relation, each plate having a row of openings extending therethrough, longitudinally of the plate on each side of the longitudinal axis of the plates, the corresponding holes in the several plates being aligned, a series of tubes, one extending through each of the aligned holes of the several plates, the tubes extending transversely of the heater unit and being of a length greater than the width of the unit, and a strip of metal in 10 each of the spaces between the plates contacting with the tubes and joined to the plates.

2. A heating unit for drying chambers of the type described comprising a plurality of metal plates spaced apart and arranged in parallel 15 relation, and a pair of strips of metal in each of the spaces between the plates and closing the spaces between the plates to form chambers, the strips of metal being undulating and the corresponding strips between the several plates being 20 aligned.

3. A heating unit for drying chambers of the type described comprising a plurality of metal plates spaced apart and arranged in parallel relation, each plate having an undulating row of 25 openings therethrough, extending longitudinally of the plate on each side of the longitudinal axis of the plate, the corresponding openings in the several plates being aligned, a series of tubes extending transversely of the plates, one extending 30 through each of the aligned openings of the several plates and being of a length greater than the width of the unit, and a pair of strips of metal in each of the spaces between the plates closing 35 the spaces between the plates, each strip of a 40 pair contacting with each of the tubes of one row of the tubes extending through the plates.

4. A heating unit as described in claim 1, the plates of which have stepped edges for joining 45 several heating units together to form a baffle.
